UNITED STATES PATENT OFFICE.

JOHN PURSEY GILBANKS, OF NEW YORK, N. Y.

DESIGN FOR A FLOWER-HOLDER.

54,077.

Specification for Design.

Patented Nov. 4, 1919.

Application filed April 4, 1919. Serial No. 287,643. Term of patent 7 years.

To all whom it may concern:

Be it known that I, JOHN P. GILBANKS, a citizen of the United States, and residing at New York, county of New York, State of New York, have invented a new, original, and ornamental Design for Flower-Holders, of which the following is a specification, reference being had to the accompanying drawing, forming part thereof.

The figure is a perspective view of a flower holder showing my new design.

I claim,—

The ornamental design for a flower holder as shown.

In testimony whereof I have hereunto set my hand on this 27th day of March, A. D. 1919.

JOHN PURSEY GILBANKS.
